Primary Examiner — Mary Shannon Malley*Assistant Examiner* — Michelle Marquart Christeon(74) *Attorney, Agent, or Firm* — Olive Law Group, PLLC(57) **CLAIM**

The ornamental design for a chair, as shown and described.

DESCRIPTION

FIG. 1 is a front perspective view of a chair;

FIG. 2 is another front perspective view thereof, showing the chair in its environment;

FIG. 3 is a front view thereof;

FIG. 4 is a rear view thereof;

FIG. 5 is a right side view thereof;

FIG. 6 is a left side view thereof; and,

FIG. 7 is a top view thereof.

The long dash broken lines show environment and portions of the chair that forms no part of the claimed design. The short dash broken lines represent stitching that does not form part of the claimed design.

1 Claim, 7 Drawing Sheets(56)
